(57) **CLAIM**

The ornamental design for a front bumper bar for a snowmobile, as shown and described.

DESCRIPTION

FIG. 1 is a front right perspective view of a front bumper bar for a snowmobile;

FIG. 2 is an enlarged front-right perspective view thereof;

FIG. 3 is a rear left perspective view thereof;

FIG. 4 is a right side view thereof;

FIG. 5 is a left side view thereof;

FIG. 6 is a front view thereof;

FIG. 7 is a top plan view thereof; and

FIG. 8 is a bottom plan view thereof.

The broken line showing a snowmobile is included for the purpose of illustrating only and forms no part of the claimed design.
